Patented Sept. 18, 1917.

UNITED STATES PATENT OFFICE.

CHARLES WOLF, OF SPOKANE, WASHINGTON, ASSIGNOR TO EUREKA SILO COMPANY,
OF BELLINGHAM, WASHINGTON.

SILO CONSTRUCTION.

1,240,284.

Specification of Letters Patent. Patented Sept. 18, 1917.

Application filed May 19, 1917. Serial No. 169,743.

To all whom it may concern:

Be it known that I, CHARLES WOLF, a citizen of the United States, residing at Spokane, in the county of Spokane and State of Washington, have invented certain new and useful Improvements in Silo Constructions, of which the following is a specification.

My invention relates to improvements in silo constructions and has to do more particularly with the design of the wall supporting uprights which enter into the construction of silos of polygonal or substantially circular shape.

The principal object of the invention resides in the provision of a novel and advantageous form of upright and splineway or slot for the vertical spline which serves to key the joined sections of the upright together, and of a spline of the required shape 20 in transverse section to fit the slot.

The main point of difference between the upright keying means herein set forth and corresponding elements of previous constructions known to be in use resides most particularly in the specific shape of the spline slot and spline. Heretofore it has been the practice to cut a three sided slot or groove in each of the engaging faces of the upright sections, which forms of slot or groove when 30 the sections are in position, register to provide an angular splineway which necessitates an angularly shaped spline. When shrinkage or expansion takes place such a spline frequently splits down the center by 35 reason of the shearing action which then occurs, so that the spline utterly fails of its intended purpose of retaining the silo structure rigid and tight. Leakage of air through the splits and resultant open seams 40 cause rapid deterioration of the silage, especially that portion which is immediately subjected to the air drafts.

There is a further most important consideration which must be dealt with by silo manufacturers. This has to do with the 45 milling of the uprights. I provide an upright whose faces and splineway may be cut on the standard sticker or planer. The splineway most commonly used is formed by 50 cutting a three sided groove in each of the joined upright sections which, when the sections are fitted together provides a six sided or faced splineway angularly shaped in cross-section and requiring a correspondingly formed spline as heretofore outlined.

The only excuse for such a shaped splineway and spline is due to the fact that a special machine would be required for cutting the registering three sided grooves at such an angle to the engaging faces of the 60 upright sections as to provide a rectangular splineway adapted to receive a rectangular spline. Such a special machine with slanting knives and heads could possibly be constructed but it would be extremely costly 65 and its use limited. When employing a straight arbor only two sides of a three sided slot or groove could be milled properly at the desired angle, the third side being chamfered off and requiring a spline of unsatisfactory design.

As regards cost of manufacture it should be here stated that the silo industry has grown to be a substantial one and the keen competition in the trade renders it imperative to minimize the cost of manufacture and marketing to the utmost. It is therefore the practice of silo manufacturers to mill the various parts as near as possible to the market to avoid large freight charges. 75 Hence it is important that standard equipped mills in the different market centers throughout the country be utilized to furnish the parts. It would not be feasible for reasons of economy to equip such mills with 80 special machines.

The foregoing explanation indicates briefly the advantages of the present construction over existing ones, but the same will be hereinafter more explicitly pointed 85 out in connection with the accompanying drawings, in which—

Figure 1 is a horizontal section taken through two of the silo uprights and showing the silo wall construction fragmentally, 95 the spline which keys the upright sections in place, and the manner of securing the sidings or wall boards to the uprights.

Fig. 2 is an enlarged sectional view through the upright.

Fig. 3 is an end view of an upright section, the same being shown in solid lines, while dash lines indicate the rectangular blank in the position it is placed on a planer or like machine for cutting, the purpose being to indicate the top, bottom, and vertical edge cuts made in forming the upright sections from the blank.

Referring more specifically to the drawings in which like reference characters in

dicate like parts in the several views, the numeral 1 designates the upright sections which are keyed together by a rectangular spline 2. The companion sections of the uprights are of wedge design in transverse section as shown, the engaging flat faces 3 being cut to taper at an angle to their opposite faces and formed with V-shaped grooves adapted to register to provide a splineway of rectangular or diamond shape, the grooves being indicated by the numeral 4. The outer board supporting faces 5 of the sections are provided with outer wall board supporting grooves 6 and inner wall board supporting grooves 7 cut at right angles to their respective face. The outer exposed faces 8 of the sections are chamfered off in the planing process to present a neat, flush surface with respect to the outer wall boards 9 of the silo. The inner exposed faces of the sections are preferably beveled off as indicated at 10.

In the section forming process wherein a standard planer is utilized, and referring for the purpose of description to Fig. 3 of the drawings, the tapered face 3, the V-shaped splineway groove 4, and the outer exposed face 8 of the section is cut by the top knife or knives of the machine, while the grooves 6 and 7 and the inner exposed beveled face 10 are cut by the bottom knife or knives of the machine. Thus the splineway grooves or slots may be cut with a knife mounted upon a planer head parallel to the machine. The old form of three-sided groove is necessarily made by tilting the head and as very few standard machines have provision for such tilting manufacture is therefore limited to specially equipped mills. With the present splineway groove, by running the upright member through the machine with the face 5 upon the planed bed the grooves 6 and 7 will be cut square with respect to the face. A beveled knife will serve to form the opposite face 3 and to cut the V-shaped splineway groove in one operation.

I do not claim as my invention the mere provision of a rectangular spline uniting two joined bodies of indefinite design but, on the contrary, it is to be understood that my invention resides in the combination of a substantially trapezoidal or wedge-shaped upright composed of joined tapered sections and a splineway of practical shape formed of registering V-shaped grooves in the en-

gaging faces of the upright sections, which grooves are so related to the angle of the engaging faces as to render the sections capable of being milled on machines of standard types.

It is, of course, to be further understood that the primary aim of the invention is the provision of a spline possessing greater strength than those heretofore used in silo or like structures, irrespective of the practicability of its manufacture and the economic considerations involved; it being apparent that the spline may be so cut and disposed between the upright sections that the grain of the timber will be at substantially right angles to the line of the engaging faces of the sections to provide a strong resistance to any shearing action between the sections.

I claim as my invention:

1. A wall supporting upright for silos composed of longitudinal companion sections of similar design adapted to be keyed together by a longitudinal spline, each of said sections being substantially wedge shaped in transverse section and having its outer board supporting face provided with longitudinal board supporting grooves and its opposite or section engaging face provided with a longitudinal V-shaped groove, the V-shaped grooves of the joined sections being adapted to register to provide a longitudinal splineway, and a spline adapted to fit in said splineway.

2. A wall supporting upright for silos of polygonal construction, composed of longitudinal companion sections of similar design adapted to be keyed together by a longitudinal spline, each of said sections being formed with a straight outer board supporting face and an opposite or section engaging face tapered at an angle to the straight face, the outer board supporting face being provided with longitudinal board supporting grooves cut rectangular with respect to the face, and its opposite section engaging face provided with a longitudinal V-shaped groove, the V-shaped grooves of the joined sections being adapted to register to provide a longitudinal splineway when the sections are assembled, and a spline adapted to fit in said splineway.

In testimony whereof I affix my signature.

CHARLES WOLF.
